UNITED STATES PATENT OFFICE.

DAVID FRANK, OF NEW YORK, N. Y., ASSIGNOR OF ONE-HALF TO JOHN TROUNSTINE, OF SAME PLACE.

DESIGN FOR AN END FRAME FOR BEDSTEADS.

SPECIFICATION forming part of Design No. 33,961, dated January 22, 1901.

Application filed December 26, 1900. Serial No. 41,162. Term of patent 7 years.

To all whom it may concern:

Be it known that I, DAVID FRANK, a citizen of the United States, residing at New York, (Brooklyn,) Kings county, State of New York, have invented and produced a new and original Design for an End Frame for Bedsteads, of which the following is a specification, reference being had to the accompanying drawing, forming a part thereof, and in which is represented a perspective view of an end frame for bedsteads bearing and incorporating my design.

The leading features of my design consist of the form and ornamental configuration of the end frame, substantially as shown.

In the drawing, A A designate the corner-posts of the end frame, B B the transverse rods of usual character extending intermediate said corner-posts, and C C the usual vertical rods extending intermediate the transverse rods B B.

The distinctive ornamental part of the present design is located above the upper rod B and comprises the substantially circular central panel D and the curved framings E E, 25 extending from the body of the corner-posts A A inward to the sides of said panel D, substantially as shown. Within the outlines or fields defined in part by the framings E E are the ornamental scrolls F, and within the panel 30 D are the scroll G, central bar H, and short bars I, as illustrated.

What I claim is—

The design for an end frame for bedsteads, substantially as shown and described.

Signed at New York, (Brooklyn,) in the county of Kings and State of New York, this 22d day of December, 1900.

DAVID FRANK.
